(57) CLAIM

The ornamental design for a capsule, as shown and described.

DESCRIPTION

FIG. 1 is a front perspective view of a capsule showing my new design;

FIG. 2 is a rear perspective view thereof;

FIG. 3 is a front view thereof;

FIG. 4 is a rear view thereof;

FIG. 5 is a right side view thereof;

FIG. 6 is a left side thereof;

FIG. 7 is a top view thereof;

FIG. 8 is a bottom view thereof;

FIG. 9 is another top view thereof, showing the word "TEXT" in broken lines;

FIG. 10 is a front perspective view of the capsule shown in an alternate environment; and,

FIG. 11 is a front perspective view of the capsule shown in another environment of use.

The drawings include relatively thin surface shading lines which represent contour, not surface ornamentation. The diagonal parallel shading lines represent a transparent surface. The horizontal parallel shading lines represent an opaque surface. The dashed broken lines illustrate structure or features that form no part of the claimed design.
